AUTO WINDOW SCREEN

Anton M. Yurkovich, Cleveland, Ohio

Application September 21, 1936, Serial No. 101,709

3 Claims. (Cl. 156—14)

This invention relates to a window screen for automotive vehicles and especially a window screen which will not interfere with the normal use, that is raising and lowering, of the window 5 of the vehicle. This therefore is the general object of the present invention.

Another object of the present invention is to provide a window screen for an automotive vehicle, which screen may be easily positioned on 10 the vehicle, easily removed therefrom, and yet when in position will not jar loose due to the vibration of the vehicle.

A further object is to provide a window screen for an automotive vehicle which may be positioned on the vehicle while the car is in motion, and which will permit the raising of the vehicle window without necessitating the removal of the screen, and wherein, when the window is raised and the car locked the screen will be entirely 20 within the car, thereby preventing theft of the screen.

Other objects of the present invention will be brought out in the specification which refers to a preferred form of the invention as illustrated in the drawing. The novel features of the invention will be set forth in the claims.

Referring now to the drawing, Fig. 1 is a view of an automotive vehicle and illustrates my screen in use;

Fig. 2 is a plan view of my improved screen; Fig. 3 is a sectional view of my improved screen in use, the plane of the section being indicated by the lines 3—3 on Fig. 1;

Fig. 4 is an enlarged sectional detail as indicated by the lines 4—4 on Fig. 2;

Fig. 5 is a perspective view of one of the screen positioning members.

Referring again to the drawing it will be seen that my improved screen comprises a sheet of wire fabric, 16, bound at its edges by U shaped binding strips 11 which are secured together and to the screen by rivets 12, and secured together as at 11^a by spot welding. The binding strips are made of a comparatively thin metal strip turned 45 back on itself. The shape and size of the screen is of course determined by the shape and size of the window frame with which the screen is to be used.

At its uppermost edge the screen binding extends above the upper limits of the screen material and is there pinched together to form a thin 50 upwardly extending lip 14 which may be inserted between the glass protecting felt strip 15 and the window frame 16 of an automotive vehicle A as illustrated in Fig. 3.

The screen is of such height that when its upper edge is inserted in the window frame its lower edge may be rocked in position. Secured to the screen by rivets 21 are a pair of vertically extending strips 20, the upper ends of which bend 5 outwardly and upwardly as to form hooks 22 which engage the inner side of the window frame at the top thereof, as shown in Fig. 3. The lower ends of these strips are riveted to the screen by rivets 23 and do not extend to the lower edge 10 of the screen, stopping short thereof as indicated at 44 in Fig. 2.

Each strip 20 has secured thereto adjacent its lower end a threaded stud 24 adapted to coact with a locking member 25 and a suitable wing nut 15 26 to secure the screen in position in the window frame.

The locking member or clamp 25 is best illustrated in Figs. 4 and 5. As there shown the locking member comprises a stamping having a 20 body portion 38, having a vertically extending slot 31 formed by outwardly stamped walls 32. This slot is shaped to permit the clamp to be moved vertically on the stud 24 of its respective strip 20. 25

To guide the movement of the clamp the body portion thereof is provided along its vertically extending edges, with inwardly turned lips 35 arranged to embrace the vertical edges of its respective strip 20. Each clamp, adjacent its 30 upper end is provided with a hook like portion 36 which is bent outwardly from the body 38 and provides a handle by means of which the clamp is raised or lowered.

The clamp provides the means for positioning the lower edge of the screen in the window frame. As shown in Figs. 4 and 5 the clamp is provided with a pair of prongs 38 which are bent inwardly and then downwardly. Intermediate the prongs 40 the clamp is provided with a hook portion 38 which is bent outwardly and then downwardly from the body 38 of the clamp. 35

When the upper edge of the screen has been positioned as heretofore described the clamps are slid downwardly on their studs 24 and the prongs 38 shoved between the glass protecting felt strip 15 and the inner face of the window frame 16. The hook then engages the window frame as shown in Fig. 3. The wing nuts 26 are then 50 tightened, thereby securing the clamp in position on the screen and likewise securing the screen against movement in the window frame.

My improved screen is secured to the frame from the inside of the car and I have found that 55

the glass, which lies outside of the screen, may be raised and lowered without difficulty.

Having set forth the principles of my invention, and described and illustrated an embodiment thereof for practical use, what I claim and desire to secure by Letters Patent, is,—

- 10 1. A screen for automotive vehicle windows comprising a sheet of screen fabric, a pair of vertically extending strips secured thereto, the upper end of each strip and the upper edge of the screen fabric being formed to embrace the upper edge of an automotive window frame, and means slidably carried by the lower ends of said strips and arranged and adapted to embrace the lower edge of the window frame by engaging opposite faces thereof, and means to secure said movable means to their respective strips.
- 15 2. A screen for an automotive vehicle window having a window frame and glass protecting stripes carried thereby, said screen comprising a substantially rectangular sheet of wire screen fabric, a pair of spaced vertically extending narrow metallic strips secured thereto, the upper end of each strip being bent outwardly and then upwardly to engage the inner surface of an automotive window frame when the upper edge of said screen is inserted between the window frame member and a glass protecting strip, each of said strips being provided adjacent its lower end with a threaded outwardly extending stud, a pair of clamping members, each having a slotted opening therein to slidably engage respective studs,

each clamp being provided with a pair of spaced inwardly turned tongues to slidably engage the edges of respective strips to prevent relative rotation between a strip and a clamp, each clamp being provided with an outwardly and then downwardly extending prong adapted to be inserted between a window frame member and its associated glass protecting strip, each clamp also having an outward and then downward tongue to engage the window frame and wing nuts 10 threadingly mounted on said respective strips to secure the clamps to their respective strips.

3. A screen for automotive vehicle windows comprising a sheet of screen fabric, a thin metallic U-shaped frame embracing the edges of said fabric, and extending above the upper reach of said fabric for insertion in an automotive window frame, a pair of vertically extending strips secured to said frame, the upper end of each strip extending above the upper edge of said frame 20 and being bent outwardly and then upwardly to engage the inner surface edge of the window frame, threaded studs carried by respective strips adjacent their lower ends, clamps mounted for vertical movement on said studs and guidingly 25 embracing their respective strips, each clamp being provided with means to engage opposite faces of the lower edge of the window frame to prevent relative movement between the screen and the frame, and manually operable means to 30 secure said clamps to their respective strips.

ANTON M. YURKOVICH.
